 Contact Lens Regimen Cards (Year: 2025).*

(Continued)

Primary Examiner — Lauren D Mcvey(74) *Attorney, Agent, or Firm* — Renaissance IP Law Group LLP(57) **CLAIM**

The ornamental design for a card for contact lens fitting, as shown and described.

DESCRIPTION

FIG. 1 is a front view showing our new design for a card for contact lens fitting; and,
 FIG. 2 is a rear view thereof.

The thickness forms no part of the claimed design.
 The broken lines depict portions of the card for contact lens that form no part of the claimed design.
